Specification for Design.

Patented Nov. 28, 1916.

Application filed August 31, 1916. Serial No. 117,947. Term of patent 14 years.

To all whom it may concern:

Be it known that I, VICTOR A. PARKER, a citizen of the United States, residing at Akron, in the county of Summit and State of Ohio, have invented a new, original, and ornamental Design for Tread-Bands for Pneumatic Tires, of which the following is a specification, reference being had to the accompanying drawings, forming a part thereof.

In the drawings, Figure 1 represents a

plan view of a tread band embodying my invention and shown in a flattened or distended condition. Fig. 2 represents a cross-sectional view of the band in its natural or curved position and taken on the line 2—2 of Fig. 1.

I claim:

The ornamental design for a tread band for pneumatic tires as shown.

VICTOR A. PARKER.
